UNITED STATES PATENT OFFICE.

RAYMOND G. McALLISTER, OF PAINTED POST, NEW YORK, ASSIGNOR TO INGERSOLL-RAND COMPANY, OF JERSEY CITY, NEW JERSEY, A CORPORATION OF NEW JERSEY.

CENTRIFUGAL UNLOADER.

Application filed October 3, 1925. Serial No. 60,142.

This invention relates to air compressor unloaders, and more particularly to that type which is adapted to unload the compressor to enable the driving element to accelerate before loading the compressor.

Electric motors or internal combustion engines, as is well known, have low starting torque. In cases in which they are used for driving air compressors it is desirable that the load be removed in order either to permit the engine to accelerate, in the case of an internal combustion engine, or, in the case of an electric motor, to prevent heavy drafts of current at starting.

One object of this invention is to unload the compressor while the motor is accelerating by means which at high speeds of the motor disengage, so that there are no wearing parts engaged while the compressor is operating at normal speed.

Other objects and advantages of the invention will be in part obvious and in part pointed out hereinafter.

In the drawing forming part of this specification in which similar reference characters refer to similar parts,

Figure 1 is a longitudinal vertical section through a compressor provided with an unloader constructed in accordance with the practice of the invention.

Figure 2 is a view of the compressor, the unloader being shown in section along the line 2-2 looking in the direction of the arrows, and

Figure 3 is a cross section of the unloader along the line 3-3 looking in the direction of the arrows.

Referring to the drawing, the compressor includes a casing A having cylinders B formed integrally therewith, and a crank shaft C provided with main bearings D, and cranks E for operating the pistons F in the cylinders B. A cylinder head G houses the intake valve assemblies for the cylinders B, each valve assembly including a valve seat, H, an inlet valve J and a valve back stop K suitably held together by a bolt L. The valve seats H are held in position in apertures O by means of cages P which are screwed into a threaded aperture Q in the head G. For unloading the compressor the valves J are adapted to be pressed from their seats H by spiders R provided with plungers S arranged to slide in guides T mounted in suitable apertures U of the cages

P. Pins V extend into the guides T and are adapted to press against the upper faces of the plungers S to depress the spiders R for pressing the valves J from their seats. The interior of the cages P is adapted to communicate with the inlet manifold W through a plurality of apertures X in the walls of the cage P.

In accordance with the practice of this invention the unloading mechanism is operated through a medium of a shaft Y driven by the compressor through a gear Z mounted at the end of the crank shaft C and a pinion b keyed to the shaft Y. The shaft Y is journalled in a boss d preferably formed integrally with a cover e attached in any suitable manner to the end of the crank case A. A disc f is loosely mounted on the exterior of the boss or journal d concentrically with the shaft Y and is attached by means of a suitable pin g remote from the center of rotation of the disc f to a system of links and levers comprising a link h, a lever j connected to a lay shaft k having arms o adapted to press against pins V for opening the compressor valves K. Upon rotation of the disc f in a counterclockwise direction, the link h is pulled downwardly, thereby opening the compressor valves. Upon rotation of the disc f in a clockwise direction, the pin g assumes a position at the opposite side of the shaft Y whereupon the link h is similarly held down. It will be seen therefore that the compressor valves are opened upon rotation of the disc f in either direction.

The disc f is adapted to be actuated or rotated by one or more weights p which are spring pressed, as for instance by means of a coil spring q, to grip the disc f. A suitable slot r may be formed in the periphery of the weights p to admit the coil spring q so that the spring lies embedded in the weights p. In order to rotate the weights p, a cover s keyed to the end of the shaft Y is provided with inwardly projecting pins t engaging slots u in the faces of the links p. The slots u extend radially and permit the weights p to move radially outward and away from the disc f. Longitudinal movement of the weights p is prevented in either direction by the cover s and by a flange v of the disc f. If desired, a layer of suitable friction material w may be attached to the periphery of the disc f to form a good grip-

ping surface for the weights p against the disc f .

In operation at slow speeds of the crank shaft C , such as at starting of the compressor actuating motor (not shown), the shaft Y rotates at a relatively slow speed transmitting rotation through the cover s and the pin t to the weights p surrounding the disc f . The spring q presses the weights p 10 against the disc f tending to rotate the disc and therefore pulling on the link h to open the compressor valve. As the compressor operating motor speeds up, the shaft Y rotates more rapidly and by centrifugal force 15 the weights p overcome the tension in the spring q , causing the weights to fly outwardly disengaging the disc f , whereupon the link h , being released, permits the spider R to disengage the valve K permitting them 20 to function normally. While operating at high speed the disc f is free and there are no engaging surfaces to wear out. The outward movement of the weights p is limited by the circular flange x surrounding the 25 weights and formed integrally with the cover s .

The compressor operating motor (not shown) may be connected to the crank shaft C at the fly wheel y located on the crank shaft C exterior to the casing A .

When operating normally the spiders R are held out of contact with the valves J by coil springs z within the spiders R and pressing against the valve seats H . The unloading mechanism above described operates 30 against the tension of these springs to hold the valves J off their seats H .

I claim:

1. In combination with a compressor and its valves, a shaft adapted to be rotated by the compressor, a disc journaled concentrically with the shaft, a weight rotated by the shaft and spring pressed to engage said disc at slow speeds and disengaged by centrifugal force from said disc at high speed 45 of the shaft, and a system of links and levers associated with said disc for opening said compressor valves.

2. In combination with a compressor and its valves, a shaft adapted to be rotated by the compressor, a disc journaled concentrically with the shaft, a plurality of weights rotated by said shaft surrounding said disc, said weights being spring pressed to engage said disc frictionally at slow 50 speeds of the shaft and disengaged by centrifugal force from said disc at high speeds 55 of the shaft, and a system of links and levers associated with said disc for opening said compressor valves.

3. In combination with a compressor and its valves, a shaft adapted to be rotated by a compressor, a disc journaled concentrically with the shaft, a cover rigidly attached to the shaft, weights within said cover attached thereto and spring pressed to engage said disc at slow speeds of the shaft and adapted to be disengaged by centrifugal force from said disc at high speeds, a link 65 attached to said disc, a lay shaft adjacent 70 the valves to be operated by said link, and means associated with said lay shaft to open said compressor valves.

In testimony whereof I have signed this specification.

RAYMOND C. McALLISTER.
